[57] CLAIM

The ornamental design for a transparent soft rubber ring device to be worn on the second knuckle of a wearer for operating push buttons, as shown and described.

DESCRIPTION

FIG. 1 is a front elevational view of the transparent soft rubber ring device to be worn on the second knuckle of a wearer for operating push buttons showing my new design;

FIG. 2 is a rear elevational view thereof;

FIG. 3 is a right view thereof;

FIG. 4 is a left view thereof;

FIG. 5 is a top plan view thereof; and,

FIG. 6 is a bottom plan view thereof.

The broken line showing of a finger in FIG. 3 is for illustrative purposes only and forms no part of the claimed design.
